UNITED STATES PATENT OFFICE.

ALLEN LOOMIS, OF DETROIT, MICHIGAN, ASSIGNOR TO PACKARD MOTOR CAR COMPANY, OF DETROIT, MICHIGAN, A CORPORATION OF MICHIGAN.

MOTOR-VEHICLE.

1,209,863.

Specification of Letters Patent. Patented Dec. 26, 1916.

Application filed November 6, 1912. Serial No. 729,787.

To all whom it may concern:

Be it known that I, ALLEN LOOMIS, a citizen of the United States, and resident of Detroit, Wayne county, State of Michigan, have invented certain new and useful Improvements in Motor-Vehicles, of which the following is a specification.

This invention relates to motor vehicles, and particularly to the front end construction of the motor and the adjacent parts of the vehicle frame.

One of the objects of the present invention is to construct the front end of the crank case of a hydrocarbon motor so that it shall form a suitable housing for the timing gearing, which housing shall be accessible both from the front and from the top.

Another object of the invention is to construct a hydrocarbon motor having a crank shaft, a cam shaft, and an auxiliary shaft 20 triangularly arranged and driven by silent chain gearing, with an integral extension from the crank case forming a housing around the chain gear mechanism, which 25 housing is provided with a removable top cover, whereby the chain may be inspected and removed and replaced.

Another object of the invention is to form the top cover of the timing gear casing of 30 a hydrocarbon motor so that it will form a lock for the supporting pivot pin of the motor crank case.

Another object of the invention is to form 35 a cover for the above construction so that it will also support the cooling fan of the motor.

Another object of the invention is to provide a motor vehicle crank case, in which the upper part is adapted to carry the upper 40 half of the crank shaft bearings, and in which a bottom bearing receiving member carries the lower half of the front bearing of the crank shaft and is formed with a forwardly extending wall, which forms the 45 bottom of the motor gear case.

Another object of the invention is to mount the pump shaft or other auxiliary shaft of a hydrocarbon motor in a bearing member formed with a pair of separated 50 bearings connected by a web, and which bearing member is suitably connected to the front wall of the motor crank case.

Other objects of the invention will appear

in the following description, taken in connection with the drawings which form a 55 part of this specification, and in which,

Figure 1 is a front elevation of a motor vehicle built in accordance with this invention and having parts broken away; Fig. 2 is a vertical longitudinal sectional view 60 through the vehicle shown in Fig. 1, with some parts shown in elevation; Fig. 3 is a section approximately on the line 3—3 of Fig. 2; Fig. 4 is a horizontal section approximately on the line 4—4 of Fig. 3; and Fig. 5 is a plan view of the parts shown in Fig. 1, with the fan bracket removed.

Referring to the drawings, 10 indicates one of the side bars of a motor vehicle frame, upon which the motor is mounted. 70 The motor illustrated is of the four cycle hydrocarbon type, having its rear end suitably supported on the vehicle frame and having its front end pivotally supported on the frame through a cross beam 11 and 75 pivot pin 12. This pivot pin 12 connects the cross member 11 with a bracket 13, which is securely bolted to the upper part 14 of the crank case, as by bolts 15. The pin 12 is retained in position, as shown in 80 Fig. 2, by means of a lug 16 formed as an integral part of a cover 17, which will be hereinafter more fully described.

On the upper part 14 of the crank case, the cylinders 18 are mounted, and the crank 85 shaft 19 has its front end 20 mounted in a bearing 21, the upper half of which is supported in the upper part 14 of the crank case, as shown particularly in Fig. 2. The lower half of the bearing 21 is supported 90 in a bottom bearing receiving member 22, which is secured to the upper part 14 by a pair of clamping pieces 23 and bolts 24. The crank case or housing is completed by a bottom cover 25, which is secured to the 95 upper part 14, and forms a joint with the bearing receiving member 22 at 26, so that the oil within the crank case cannot escape. The front wall of the crank case is laterally 100 extended, as shown at 27 in Fig. 4, and forwardly extending integral webs 28 and 29 form the side walls of the timing gear casing 30. A forwardly extending integral web on the member 22 forms the bottom wall 31 of the gear casing 30, and the cover 105 17, hereinabove referred to, forms the top

wall of this casing. This latter wall is removable, being secured to the other web portions, as by bolts 32. The wall 29 is somewhat farther extended to form a wall 5 33, parallel with the wall 27, and a front cover 34, which is also removable, is secured to the walls, as by bolts 35.

The front end 20 of the crank shaft extends forwardly, beyond its bearing, and 10 has secured thereon a driving gear in the form of twin sprockets 36. A sleeve 37 and nut 38 secures the sprocket in place, the sleeve being formed with jaws 39, which cooperate with jaws 40 on the end of the 15 starting crank shaft 41, which shaft is mounted in a cup shaped member 42 secured to the cover 34. A spring 43 keeps the jaws normally separated, and a crank 44 is attached to the shaft 41 for manually operating same. A cross member 45 of the vehicle frame supports the forward end of the starting crank shaft 41, as shown clearly 20 in Fig. 2.

Suitably mounted on the vehicle frame 25 above the cross member 45, is a radiator 46 of any desired construction, and a fan 47 draws air through the radiator for increasing its efficiency. This fan is preferably operated by a belt extending from the 30 pulley 48, shown in Fig. 5, to the pulley 49, shown in Fig. 2, and the fan is rotatably mounted in an adjustable bracket 50, having a shank 51 which is secured in a boss 52 formed integral with the cover 17, herein- 35 above referred to.

A bearing member 53 is rigidly secured to the wall 27, as by bolts 54, and this member is formed with a pair of separated bearings 55 and 56 connected by webs 57, shown 40 particularly in Figs. 3 and 4. In the bearings 55 and 56 a shaft 58 is mounted, which shaft projects through the wall 33 and has the pulley 48 mounted thereon. Gears or 45 sprockets 59 are keyed to the shaft 58 for driving the same. The shaft 58 is adapted to drive any suitable auxiliary mechanism of the motor, and is shown as operating a centrifugal pump 60, the casing 61 of which pump is shown as formed as an integral 50 part of the bearing member 53, thus permitting the pump and bearing member to be cast and machined as a single piece.

The motor cam shaft 62 is mounted in a suitable bearing in the wall 27 of the crank 55 case and it is provided with a gear or twin sprocket 63, shown in dotted lines in Fig. 1, and a chain 64, preferably of the silent type, connects the three sprockets 36, 59 and 63, which sprockets are triangularly arranged 60 for this purpose, as shown in Fig. 1.

Various modifications of the invention 65 may be made without departing from the spirit thereof, and the claims are intended to be of such scope as to cover all such modifications.

Having thus described my invention, what I claim and desire to secure by Letters Patent, is,

1. The combination with a motor crank case comprising a support for the crank and auxiliary shafts and a timing gear case at its end, shafts in said supports, power transmitting mechanism connecting said shafts and adapted to be removed laterally of the shafts, said gear case having a top opening, a removable cover for said opening, and a fan mounted on said cover and driven by said auxiliary shaft. 70

2. In a motor vehicle, the combination with the frame, of a motor having an end gear casing, a supporting member secured to the frame, a pin between the supporting member and the motor for supporting the latter, and a cover for said gear casing having a part adapted to hold said pin in position. 80

3. In a motor vehicle, the combination with the frame, of a motor having an end gear casing with a top opening therein, a cross beam resting on the frame adjacent the gear end of the motor, a pin forming a pivotal connection between the motor and said beam, and a cover for said casing having a lug in contact with the head of said pin to prevent the removal of the latter. 90

4. In a hydrocarbon motor, the combination with a crank shaft, a cam shaft, an auxiliary shaft, and chain driving connections between said shafts, of a crank case supporting said shafts and having walls 100 extending at the sides and bottom of the shaft ends and driving connections, and a removable top cover for said wall extensions.

5. In a hydrocarbon motor, the combination with a crank shaft, a cam shaft, an auxiliary shaft, and chain driving connections between said shafts, of a crank case supporting said shafts and having walls 105 extending at the sides and bottom of the shaft ends and driving connections, a removable front cover therefor, and a removable top cover for said wall extensions. 110

6. In a hydrocarbon motor, the combination with a crank shaft, a cam shaft, an auxiliary shaft triangularly arranged, sprockets on the ends of said shafts, and a chain connecting all of said sprockets, of a crank case supporting said shafts in its end wall and having extensions forming a 120 casing around said sprockets and chain, and a removable top cover for said casing, whereby the chain may be inspected and removed and replaced. 115

7. In a hydrocarbon motor, the combination with a crank shaft, a cam shaft and an auxiliary shaft triangularly arranged, sprockets on the ends of said shafts, and a chain connecting all of said sprockets, of a crank case having bearings for said crank 125 130

shaft and said cam shaft, a member mounted in said crank case and provided with a bearing in which said auxiliary shaft is mounted said member being also provided with a 5 flange and means co-acting with said flange to secure the bearing member to the crank case.

8. In a motor vehicle, the combination of a crank shaft, a cam shaft and an auxiliary shaft, means operatively connecting said shafts, a crank case, said crank case having bearings for said crank shaft and said cam shaft, and a member detachably secured to said crank case and provided with 15 separate bearings in which said auxiliary shaft is mounted.

9. In a hydrocarbon motor, a crank case having an end wall, a pump secured to said end wall and having a bearing part forming 20 a pair of separated bearings connected by a web, a shaft for said pump mounted in said bearings and having a driving gear mounted thereon between said bearings, and means for operating said driving gear 25 from the motor crank shaft.

10. In a hydrocarbon motor, the combination with a crank case having an end wall and integral extensions beyond the end wall

forming a gear casing, of a bearing member mounted in the end wall and formed with 30 separated bearings connected by a web, said bearing member having a part extending into said integral extension of the crank case, a shaft mounted in said bearings, and driving gear on said shaft between said 35 bearings.

11. The combination with a motor crank shaft, of a casing therefor comprising an upper part formed to receive the upper half of the crank shaft bearings and having forwardly extending walls forming the sides of a gear casing, said bearings, a bottom bearing receiving member for the lower half of the front bearing only and having a forwardly extending wall forming the bottom 45 of said gear case, means for securing said member to said upper part with the front bearing and crank shaft end between them, and a bottom cover inclosing the cranks and secured to the upper part of the crank case. 50

In testimony whereof I affix my signature in the presence of two witnesses.

ALLEN LOOMIS.

ALFRED H. KNIGHT,
JOHN D. WILSON.
